DESIGN FOR A GOBLET OR SIMILAR ARTICLE

Rowena Reed Kostellow, Pittsburgh, Pa., assignor to United States Glass Co., Pittsburgh, Pa., a corporation of Pennsylvania

Application February 9, 1938, Serial No. 74,986

Term of patent 3½ years

To all whom it may concern:

Be it known that I, Rowena Reed Kostellow, a citizen of the United States, residing at Pittsburgh, Allegheny County, State of Pennsylvania, have invented a new, original, and ornamental Design for a Goblet or Similar Article, of which the following is a specification, reference being had to the accompanying drawing, forming a part thereof, in which:

Fig. 1 is a side elevation of a goblet embodying my new design; and,

Fig. 2 is a side elevation of the goblet shown in Fig. 1 turned through 45°.

The characteristic feature of my new design is shown in full lines in the drawing.

What I claim is:

The ornamental design for a goblet or similar article substantially as shown and described.

ROWENA REED KOSTELLOW.
